TYPEWRITING MACHINE

George F. Handley, Glendale, N. Y., assignor to
 Royal Typewriter Company, Inc., New York,
 N. Y., a corporation of New York

Application August 28, 1937, Serial No. 161,514

46 Claims. (Cl. 197—84)

This invention relates to improvements in typewriting machines generally, although more particularly to a carriage feeding mechanism for uniformly spacing typed characters of unjustified lines so that they are equally spaced, whereby a uniform margin will be established at the right hand end of the lines.

One of the objects of the invention is to provide a multiplying lever having pivotal connections with the rack bar and the carriage whereby the step movement of the rack bar will be transmitted to the carriage and the latter will be moved longitudinally with respect to the rack bar for a predetermined distance.

Another object of the invention is to provide control means for varying the distance of the carriage pivot relative to the rack bar pivot whereby the multiplying lever during the travel of the carriage along a predetermined distance will move the carriage longitudinally relative to the rack bar for a distance equal to a predetermined number of character spaces and thereby uniformly space all of the characters in a justified line of predetermined length.

With these and other objects in view which will more fully appear, the nature of the invention will be more clearly understood by following the description, the appended claims, and the several views illustrated in the accompanying drawings.

In the drawings:

Figure 1 is a top plan view showing a portion of the machine frame, the carriage, the escapement mechanism therefor, and my associated invention.

Figure 2 is an end elevation thereof, certain parts being shown in section.

Figure 3 is an enlarged view of the usual escapement mechanism,

Figure 4 is a front elevation of the structure shown in Figure 2, certain parts being shown in section.

Figure 5 is a cross-section taken on the line 5—5 of Figure 1.

Figure 6 is a horizontal section taken on the line 6—6 of Figure 2.

Figure 7 is a horizontal section taken on the line 7—7 of Figure 2, and

Figure 8 is a developed view of the rotary control means.

Like reference numerals designate corresponding parts throughout the several figures of the drawings.

My invention is especially applicable to a Royal standard typewriter, although it may be em-

ployed with typewriting machines of other manufacture, and in the accompanying drawings I have illustrated only that much of a typewriting machine as is necessary to a clear understanding of my invention.

The usual typewriting machine includes a main frame A which supports a track 5 on which is mounted a carriage B having end plates 6, 7, in which is journaled a platen 8, the carriage being reciprocal longitudinally along the track from one side of the main frame to the other. The carriage is urged towards the left by the usual spring motor (not shown), and is manually moved to the right, the carriage being moved intermittently to the left at uniform distances upon release of an escapement. The usual Royal escapement includes a rack bar which is mounted on the carriage in a manner to prevent any relative longitudinal movement of the carriage whereby upon depressions of any key lever or spacing bar, the escapement mechanism will be actuated and will produce definite longitudinal steps or character space movements to the carriage.

In the present instance, manually controllable means are provided for varying the carriage step relative to the escapement controlled rack bar whereby the carriage will be moved farther to the left than the rack bar during each step movement of the latter. To this end, the rack bar 9 is secured to a rack bail 10 having rearwardly extending supporting arms 11, 12 at its ends. These arms are slidably and pivotally mounted on pivot studs 13, 14 which are rigidly mounted on the end plates 6, 7 and project inwardly therefrom. Yokes 15, 16 are respectively fulcrumed on the studs 13, 14, each yoke including spaced inner and outer arms 17, 18 and a rigidly connected tie bar 19. The arms 11, 12 of the rack bail are respectively disposed between the arms 17, 18 of the yokes, and horizontal pins 20 which are rigidly connected to the bail arms of each yoke have sliding engagements in bearing openings formed in the arms 11, 12 at points in front of the pivot studs 13, 14. The outer arms 18, 18 of said yokes terminate in rearwardly extending arms 21, 21 to which are connected the lower ends of coil springs 22, 22 which function to retain yieldably the rack bar 9 in operative engagement with the escapement pinion 23, but permitting the rack bar to be elevated and disengaged therefrom each time the escapement carriage release lever (not shown) is actuated. The pinion is journaled on a horizontal shaft 24 supported on the main

frame A, and connected to the pinion to rotate therewith is the usual escapement wheel 25 which is controlled by the fixed and movable dogs 26, 27 mounted on a dog rocker 28 and actuated in the usual manner upon depression of a key lever or the spacing bar. In Figure 1, the carriage is shown as being located at its extreme right hand position, and considerable space is provided between the bail arm 11 and the inner arm 17 of the yoke 15 and between the bail arm 12 and the outer arm 18 of the yoke 16. Consequently the carriage is capable of moving longitudinally and towards the left with respect to the rack 9 for a distance equal to a plurality of character spaces which in the present instance is seven.

Rigidly attached to the main frame A and projecting rearwardly from the upper right hand end portion thereof is a horizontal bracket arm 29, and rigidly connected to and projecting laterally from the end plate 7 of the carriage B is a horizontal bracket 30. An arm 31 is connected to the right hand end of the rack bar 9 by a horizontal pivot 32, and this arm extends longitudinally of the rack bar and is in effect a part thereof. This arm projects through an opening 33 formed in the end plate 7 and overlies the carriage bracket 30, the outer end of the arm normally being guided in a straight line during longitudinal movement of the carriage relative to the rack bar, by means of a vertical guide pin 34 fixed to the bracket 30 through the medium of a spacing collar 35 and operating in a guide slot 36 formed in and extending longitudinally of said arm.

A horizontally disposed multiplying lever 37 traverses the arm 31 of the rack bar, and is fulcrumed at its rear end on a vertical fulcrum pin 38 mounted in a spacing block 39 fixed to the rear end of the main frame bracket arm 29, the lever being provided with a longitudinal slot 40 for receiving the fulcrum pin and cooperating therewith to form a sliding fulcrum connection. The forward end of the multiplying lever 37 is forked to form spaced upper and lower longitudinal arms 41, 42 for receiving the rack bar arm 31 therebetween. The upper arm 41 is provided with a longitudinally extending slot 43 for receiving a pivot screw 44 which is secured to the rack bar arm 31, thereby forming a sliding pivotal connection between the multiplying lever and the rack bar. The guide pin 34 and pivot screw 44 both are formed with heads normally spaced above the arm 31 to provide clearance for permitting slight vertical rocking movement of the arm 31 when the latter moves pivotally relatively to the rack bail 10 incident to upward swinging of the bail about its pivots 13-14 for escapement release. Thus the bail 10 may be swung upwardly for escapement release without effecting any binding of the arm 31.

A rack plate 45 is slidably mounted on the lower carriage bracket 30 below the rack bar arm 31 for longitudinal reciprocal movements in a straight line traversing the rack bar and in a direction at an inclination to the longitudinal axis 65 of the rack bar, the plate being provided with a rack 46 along one of its longitudinal edges. The plate adjacent its front and rear ends is provided with rigidly connected and depending guides 47, 48 which have sliding engagements in slots 49, 50 formed in the bracket 30. The front end of the lower arm 42 of the multiplying lever is pivotally connected to the front end of the rack plate 45 by a pivot pin 51 which is fixed to said arm 42 and depends therefrom, the pin projecting into a 75 pivot opening 48a formed in said rack plate. It

will, therefore, be seen that the multiplying lever 37 has a sliding fulcrum on the main frame, a sliding pivotal connection with the rack bar, and a shiftable pivot with the carriage. It will be also observed that by moving the rack plate longitudinally the carriage pivot 51 will be shifted towards or from the rack bar pivot 44, and consequently the distance between said pivots and the arm ratio of the lever 37 may be varied to thereby vary the longitudinal step movement of the carriage relative to the rack bar. It will be furthermore observed that the maximum distance between the rack bar pivot 44 and the carriage pivot 51 is reached when the guide pin 48 engages the forward end of the slot 50, and that the rack plate 45 may be moved rearwardly until the carriage pivot 51 is located in axial alinement with the rack bar pivot 44, whereby the lever 37 will cease to function and the rack bar and the carriage will move in unison. Thus, when the carriage pivot 51 is positioned at its maximum distance in front of the rack bar pivot 44, and the carriage is being moved from extreme left to extreme right, an increased longitudinal movement of the carriage relative to the rack bar will be made which will be equivalent to seven character spaces, this differential movement of the carriage being uniformly distributed throughout the length of the justified writing line whereby all of the printed characters in the line will be equally spaced. By moving the carriage pivot 51 closer to the rack bar pivot 44, a differential longitudinal step movement of the carriage relative to the rack bar will be made to compensate for any character spacing less than seven.

A justified copy consists of lines of uniform length arranged with vertically alined margins, and in practice these copies may be of different widths, say, four, five, six, or seven inches.

Practice has taught that in a four inch justified line a maximum differential of four character spaces is sufficient; that in a five inch justified line a maximum differential of five character spaces is sufficient; that in a six inch justified line a maximum differential of six character spaces is sufficient; and that in a seven inch justified line a maximum differential of seven character spaces is sufficient.

It is obvious that when writing a justified line of a given length, say seven inches, the differential step movement of the carriage must be less than when writing a justified line of a lesser length, say six inches.

Therefore it is desirable to provide a control means for the multiplying lever which is adaptable for a justified line of any of said widths. To this end, an upper bracket 52 is rigidly secured to the end plate 7 of the carriage and is disposed above and in spaced relation to the lower carriage bracket 30.

A single rotary control element C is employed for varying the justified carriage step movement to meet the conditions incident to justifying copies of different widths. The control element C includes a vertical shaft 53 which is journaled in the brackets 30, 52. Fixed to the lower end of the shaft is a pinion 54 which is in constant mesh with the rack 46 of the rack plate 45, and functions upon rotation of the shaft to move said plate longitudinally, thereby shifting the carriage 70 pivot 51 towards or from the rack bar pivot 44 and effecting a justified step movement to the carriage. Fixed to the shaft 53 below the upper bracket 52 is a space-indicating cylinder 55. The periphery of the cylinder is provided with a plu- 75

rality of circumferential series *a*, *b*, *c*, and *d* of justifying space indicating numerals, the series being arranged one above the other. The numerals of each series are equally spaced, but the numerals vary in number in the different series and consequently the spacing between the numerals of one series is different from the spacing between the numerals of the other series. The series, reading downwardly, are respectively 10 related to justified copies of 5 inch width, 6 inch width, 7 inch width, and 4 inch width. The series *a* contains the numerals 0, 1, 2, 3, 4, 5; the series *b* contains the numerals 0, 1, 2, 3, 4, 5, 6; the series *c* contains the numerals 0, 1, 2, 3, 4, 5, 6, 7; and the series *d* contains the numerals 0, 1, 2, 3, 4. The numerals "0" of the four series are arranged in vertical alinement as shown in Figure 8, and the numerals 5, 6, 7, 4 of the four series are also arranged in vertical alinement as 20 shown in said figure. A spring arm 56 is pivoted on an upstanding lug 51 of the bracket 52 located in rear of the control element C, the pivot being formed by a horizontal clamping screw 58 engageable in said lug. The arm extends forwardly 25 above and on the right of the cylinder 55, and pivotally supported on the forward end of said arm by a horizontal pivot pin 59 is a swingable pointer arm 60 having a pointer finger 61 which projects laterally in front of the cylinder, the 30 end 62 of the finger being positioned centrally thereof. Thus, when the spring arm 56 is swung upwardly or downwardly the pointer arm 60 will always maintain a vertical position and the pointer finger will always cooperate properly with 35 the series of numerals on the cylinder 55.

In order to assist the operator in positioning the pointer finger 61 in cooperative relation with any one of the series *a*, *b*, *c*, or *d* of numerals, there is provided a vertically disposed indicator 40 plate 63 above the cylinder 55. This plate includes a rearwardly extending bracket arm 64 which terminates in an attaching arm 65 secured to the bracket 52 by screws 66. On the front face of this plate 63 are line indicia which consist 45 of a vertical series of spaced horizontal lines and associated numerals, which are respectively indicated at 67, 68, 69 and 70, the numerals consisting of the numbers "5", "6", "7" and "4" respectively. The lines are vertically spaced to conform to the spaces between the series *a*, *b*, *c*, and *d* of the justifying space indicating numerals which are located on the cylinder 55. A pointer 71 extends laterally from the front end of the arm 56 and is adapted to be placed in registration with any of said lines upon upward or downward movement of said arm. It will be noted that when the pointer arm 60 registers with any of the numerals "0" on the cylinder 55, the carriage pivot 51 will be disposed in axial alinement 50 with the rack bar pivot 44 and in this position a normal step movement will be imparted to the carriage by the escapement mechanism.

In operation if it is desired to reproduce an unjustified line to justified length, the arm 56 is moved upwardly or downwardly until the pointer 71 registers with the desired line length indicia on the plate 63. This movement simultaneously shifts the pointer 61 into registration with the corresponding series of justifying space indicating numerals on the cylinder 55. The operator having previously ascertained the number of character spaces to be uniformly distributed, rotates the control element C until the proper numeral is positioned in register with the end 62 of said pointer 61. This movement of the con-

trol element C causes the carriage pivot 51 to be adjusted either toward or from the rack bar pivot 44 whereby the distance between said pivots will be such as to cause the necessary justifying step movement to be imparted to the carriage.

It is desirable to releasably lock the control element C in its adjusted position, and for this purpose a cylinder 72 is fixedly secured to the shaft 53 above the upper bracket 52. The cylinder 72 is provided with a plurality of circumferential series *e*, *f*, *g*, and *h* of openings 73, the several series being arranged one above the other and the openings of each series being angularly spaced. The number of openings, however, varies in the different series, there being six openings 10 in the series *e*, seven openings in the series *f*, eight openings in the series *g*, and five openings 15 in the series *h*. The several series *e*, *f*, *g*, and *h* of openings are spaced apart corresponding to the spaced relation between the series *a*, *b*, *c*, 20 and *d* of justifying space-indicating numerals on the cylinder 55. The pivot pin 59 for the pointer arm 60 is rigidly secured to the arm 56 and the inner end thereof projects toward the cylinder 72 to form a locking pin 74 which is 25 adapted to be seated within any of the openings 73 and thereby lock the rotatable control element C in any position of adjustment. When it is desired to adjust the element C, the operator withdraws the locking pin 74 from its associated opening, swings the arm 56 upwardly or downwardly to the desired position, turns the control element C until the desired character space numeral on the cylinder 55 registers with the end 62 of the pointer 61, and then releases 30 said locking pin whereby the latter will become seated in the associated opening 73.

Means are provided for limiting the extreme upward and downward movements of the arm 56 and this means is formed by projecting the 40 arm 65 outwardly beyond the right hand edge of the upper bracket 62 to thereby form a lower stop 75, the arm thence extending upwardly on the right hand side of the arm 56 as at 76 and the free end thereof being bent inwardly as at 77 to form an upper stop, the lower stop 75 limiting the downward movement of the arm 56 whereby the locking pin 74 will register with the openings 73 of the lower series *h*, and the upper stop 77 limiting the upward movement of 50 the arm 56 whereby the locking pin will register with the openings of the upper series *e*. The connecting portion 76 serves to prevent the arm 56 from being accidentally swung too far from the right when withdrawing the locking pin 74 55 from its associated opening.

It is of course to be understood that the details of structure and arrangement of parts may be variously changed and modified without departing from the spirit and scope of my invention.

I claim:

1. A carriage feeding mechanism for type-writing machines comprising the combination with a main frame, of a carriage mounted thereon for letter space movements, an escapement mechanism for the carriage including a rack bar mounted thereon for relative longitudinal movements, and means for effecting a longitudinal movement of the carriage relative to the rack bar including a multiplying lever 65 traversing the rack bar and having a sliding pivotal connection with the rack bar intermediate the ends of the lever and in the line of movement of the rack bar, one end of the lever 70 being pivoted to the carriage on one side of the

rack bar and the other end thereof having a shiftable fulcrum connection with the main frame on the other side of the rack bar and the shorter arm of the multiplying lever being 5 between the sliding pivotal connection and the pivot of the lever on the carriage.

2. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, and means for effecting a longitudinal movement of 10 the carriage relative to the rack bar including an arm pivotally connected to one end of the rack bar and extending longitudinally thereof, and a multiplying lever traversing the arm and having a sliding pivotal connection therewith, 15 one end of the lever being pivoted on the carriage and the other end thereof being fulcrumed on the main frame.

3. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, and 20 means for effecting a longitudinal movement of the carriage relative to the rack bar including an arm pivotally connected to one end of the rack bar and extending longitudinally thereof, the outer end of the arm having a longitudinally 25 slideable connection with the carriage, and a multiplying lever traversing the arm and having a sliding pivotal connection therewith, one end of the lever being pivoted on the carriage and the other end thereof being fulcrumed on 30 the main frame.

4. A carriage feeding mechanism for typewriting machines comprising the combination with a main frame, of a carriage mounted thereon for letter space movements, an escapement mechanism for the carriage including a 35 rack bar mounted thereon for relative longitudinal movements, and means for effecting a longitudinal movement of the carriage relative to the rack bar including an arm pivotally connected to one end of the rack bar and extending longitudinally thereof, and a multiplying lever traversing said arm, the lever at one end forming upper and lower rigid arms for receiving the rack bar arm therebetween, the outer 40 end of the lower arm being pivoted on the carriage and the upper arm having a sliding pivotal connection with said rack bar arm, the other end of the lever being fulcrumed on the main frame.

5. A carriage feeding mechanism for typewriting machines comprising the combination with a main frame, of a carriage mounted thereon for letter space movements, an escapement mechanism for the carriage including a 45 rack bar mounted thereon for relative longitudinal movements, a bracket arm rigidly connected to the main frame and extending rearwardly from one end thereof, a bracket extending laterally from the adjacent end of the carriage, 50 and means for effecting a longitudinal movement of the carriage relative to the rack bar including an arm pivotally connected to the adjacent end of the rack bar and extending longitudinally of said rack bar and disposed above 55 the carriage bracket, and a multiplying lever

traversing said arm, the lever at one end forming upper and lower rigid arms for receiving the rack bar arm therebetween, the outer end of the lower arm being pivoted on the carriage bracket and the upper arm having a sliding pivotal connection with said rack bar arm, the other end of the lever being fulcrumed on the main frame bracket. 5

6. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack bar during each space movement of the latter including a pivot pin shiftably mounted on the carriage, a multiplying lever fulcrumed on the main frame and pivoted to the rack bar 20 and on said pivot pin, and carriage-mounted adjusting means for shifting said pivot pin towards and from the directional line of movement of the rack bar for varying the extent of longitudinal movement of the carriage relative to 25 the rack bar caused by predetermined movement of the carriage relative to the rack bar.

7. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack 35 bar during each space movement of the latter including a multiplying lever fulcrumed on the main frame and pivoted on the rack bar and on the carriage, and means including a rack and pinion mounted on the carriage for shifting the 40 carriage pivot towards and from the rack bar for varying the extent of the longitudinal movement of the carriage relative to said rack bar.

8. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a movement of the 50 carriage relative to the rack bar during each space movement of the latter including a multiplying lever having pivotal connections with the rack bar and with the carriage, and means for shifting said lever longitudinally to vary the distance between said pivots and thereby increase or decrease the longitudinal movement of the carriage relative to the rack bar. 55

9. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a movement of the 60 carriage relative to the rack bar during each space movement of the latter including a multiplying lever having pivotal connections with the rack bar and with the carriage, and means including a rack and pinion for shifting said lever 65 longitudinally to vary the distance between said pivots and thereby increase or decrease the longitudinal movement of the carriage relative to the rack bar.

10. A carriage feeding mechanism for typewrit- 75

ing machines comprising the combination with a main frame, of a carriage mounted thereon for letter space movements, an escapement mechanism for the carriage including a rack bar mounted thereon for relative longitudinal movements, means for effecting a movement of the carriage relative to the rack bar during each space movement of the latter including a pivot plate movably mounted on the carriage, and a multiplying lever slidably fulcrumed on the main frame and having pivotal connections with the rack bar and with the plate, and means for moving the plate and the lever to shift the carriage pivot relative to the rack bar pivot and thereby increase or decrease the longitudinal movement of the carriage relative to the rack bar.

11. A carriage feeding mechanism for type-writing machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack bar during each space movement of the latter including a multiplying lever fulcrumed on the main frame and pivoted on the rack bar and on the carriage, and means for shifting the carriage pivot towards and from the rack bar and in a line extending diagonally to the longitudinal axis of the rack bar for varying the extent of the longitudinal movement of the carriage relative to said rack bar.

12. A carriage feeding mechanism for type-writing machines comprising the combination with a main frame of a carriage mounted thereon for letter space movements, an escapement mechanism for the carriage including a rack bar mounted thereon for relative longitudinal movements, means for effecting a movement of the carriage relative to the rack bar during each space movement of the latter including a pivot plate slidably mounted on the carriage for movements in a line extending diagonally to the longitudinal axis of the rack bar, and a multiplying lever slidably fulcrumed on the main frame and having pivotal connections with the rack bar and with the plate, and means for moving the plate and the lever to shift the carriage pivot relative to the rack bar pivot and thereby increase or decrease the longitudinal movement of the carriage relative to the rack bar.

13. A carriage feeding mechanism for type-writing machines comprising the combination with a main frame, of a carriage mounted thereon for letter space movements, an escapement mechanism for the carriage including a rack bar mounted thereon for relative longitudinal movements, a bracket arm rigidly connected to the main frame and extending rearwardly from one end thereof, a bracket extending laterally from the adjacent end of the carriage, means for effecting a movement of the carriage relative to the rack bar during each space movement of the latter including a multiplying lever fulcrumed on the main frame bracket and having pivotal connections with the rack bar and with the carriage bracket, and means mounted on the carriage bracket for shifting the carriage pivot towards and from the directional line of movement of the rack bar for varying the extent of the longitudinal movement of the carriage relative to said rack bar.

14. A carriage feeding mechanism for type-writing machines comprising the combination

with a main frame, of a carriage mounted thereon for letter space movements, an escapement mechanism for the carriage including a rack bar mounted thereon for relative longitudinal movements, a bracket arm rigidly connected to the main frame and extending rearwardly from one end thereof, a bracket extending laterally from the adjacent end of the carriage, means for effecting a movement of the carriage relative to the rack bar during each space movement of the latter including a multiplying lever fulcrumed on the main frame bracket and having pivotal connections with the rack bar and with the carriage bracket, and means mounted on the carriage bracket for shifting the carriage pivot towards and from the rack bar and in a line extending diagonally to the longitudinal axis of the rack bar for varying the extent of the longitudinal movement of the carriage relative to said rack bar.

15. A carriage feeding mechanism for type-writing machines comprising the combination with a main frame, of a carriage mounted thereon for letter space movements, an escapement mechanism for the carriage including a rack bar mounted thereon for relative longitudinal movements, a bracket arm rigidly connected to the main frame and extending rearwardly from one end thereof, a bracket extending laterally from the adjacent end of the carriage, means for effecting a movement of the carriage relative to the rack bar during each space movement of the latter including a pivot plate slidably mounted on the carriage bracket for movements in a straight line extending diagonally to the longitudinal axis of the rack bar, a multiplying lever slidably fulcrumed on the main frame arm and having pivotal connections with the rack bar and with the plate, and means mounted on the carriage bracket and having a rack and pinion connection with the plate for moving the plate and the lever to shift the carriage pivot relative to the rack bar pivot and thereby increase or decrease the longitudinal movement of the carriage relative to the rack bar.

16. A carriage feeding mechanism for type-writing machines comprising the combination with a main frame, of a carriage mounted thereon for letter space movements, an escapement mechanism for the carriage including a rack bar mounted thereon for relative longitudinal movements, means for effecting a longitudinal movement of the carriage relative to the rack bar during each space movement of the latter including a multiplying lever having pivotal connections with the rack bar and with the carriage, and means for shifting the carriage pivot into axial alignment with the rack bar pivot to render said lever ineffective.

17. A carriage feeding mechanism for type-writing machines comprising the combination with a main frame, of a carriage mounted thereon for letter space movements, an escapement mechanism for the carriage including a rack bar mounted thereon for relative longitudinal movements, means for effecting a longitudinal movement of the carriage relative to the rack bar during each space movement of the latter including a multiplying lever having pivotal connections with the rack bar and with the carriage, and means for shifting the carriage pivot along a line extending diagonally to the longitudinal axis of the rack bar and into alignment with the rack bar pivot to render said lever ineffective.

18. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a longitudinal movement of the carriage relative to the rack bar during each space movement of the latter including a multiplying lever having pivotal connections with the rack bar and with the carriage, and means including a rack and pinion for shifting the carriage pivot into axial alinement with the rack bar pivot to render said lever ineffective.
19. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a longitudinal movement of the carriage relative to the rack bar during each space movement of the latter including a multiplying lever traversing the rack bar and having a pivotal connection therewith, one end of the lever being pivoted on the carriage and the other end thereof being fulcrumed on the main frame, and means for shifting said lever longitudinally to position the carriage pivot in axial alinement with the rack bar pivot to thereby render said lever ineffective.
20. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a longitudinal movement of the carriage relative to the rack bar during each space movement of the latter including a multiplying lever traversing the rack bar and having a pivotal connection therewith, one end of the lever being pivoted on the carriage and the other end thereof being fulcrumed on the main frame, and means including a rack and pinion for shifting said lever longitudinally to position the carriage pivot in axial alinement with the rack bar pivot to thereby render said lever ineffective.
21. A carriage feeding mechanism for typewriting machines comprising the combination with a main frame, of a carriage mounted thereon for letter space movements, an escapement mechanism for the carriage including a rack bar mounted thereon for relative longitudinal movements, a bracket arm rigidly connected to the main frame and extending rearwardly from one end thereof, a bracket extending laterally from the adjacent end of the carriage, means for effecting a longitudinal movement of the carriage relative to the rack bar during each space movement of the latter including a pivot plate movably mounted on the carriage bracket, a multiplying lever slidably fulcrumed on the main frame arm and having pivotal connections with the rack bar and with the plate, and means including a rack and pinion connection with the plate for moving the plate together with its pivot whereby the latter will be positioned in axial alinement with the rack bar pivot to render the lever ineffective.
22. A carriage feeding mechanism for typewriting machines comprising the combination with a main frame, of a carriage mounted thereon for letter space movements, an escapement mech-

nism for the carriage including a rack bar mounted thereon for relative longitudinal movements, means for effecting a longitudinal movement of the carriage relative to the rack bar during each space movement of the latter including a multiplying lever fulcrumed on the main frame and pivoted on the rack bar and on the carriage, and means for shifting the carriage pivot towards and from the rack bar for varying the extent of the longitudinal movement of the carriage relative to said rack bar or for shifting the carriage pivot into alinement with the rack bar pivot to render said lever ineffective.

23. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a movement of the carriage relative to the rack bar during each space movement of the latter including a multiplying lever fulcrumed on the main frame and pivoted on the rack bar and on the carriage, and means including a rack and pinion for shifting the carriage pivot towards and from the rack bar for varying the extent of the longitudinal movement of the carriage relative to said rack bar or for shifting the carriage pivot into alinement with the rack bar pivot to render said lever ineffective.

24. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a movement of the carriage relative to the rack bar during each space movement of the latter including a multiplying lever having pivotal connections with the rack bar and with the carriage, and means for shifting said lever longitudinally to vary the distance between said pivots and thereby increase or decrease the longitudinal movement of the carriage relative to the rack bar or for shifting the carriage pivot into alinement with the rack bar pivot to render said lever ineffective.

25. A carriage feeding mechanism for typewriting machines comprising the combination with a main frame, of a carriage mounted thereon for letter space movements, an escapement mechanism for the carriage including a rack bar mounted thereon for relative longitudinal movements, a bracket arm rigidly connected to the main frame and extending rearwardly from one end thereof, a bracket extending laterally from the adjacent end of the carriage, means for effecting a movement of the carriage relative to the rack bar during each space movement of the latter including a pivot plate slidably mounted on the carriage bracket for movements in a straight line extending diagonally to the longitudinal axis of the rack bar, a multiplying lever slidably fulcrumed on the main frame arm and having pivotal connections with the rack bar and with the plate, and means mounted on the carriage bracket and having a rack and pinion connection with the plate for moving the plate and the lever to shift the carriage pivot relative to the rack bar pivot and thereby increase or decrease the longitudinal movement of the carriage relative to the rack bar or for shifting the carriage pivot into alinement with the rack bar pivot to render said lever ineffective.

26. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a longitudinal movement of the carriage relative to the rack bar during each space movement of the latter including a multiplying lever fulcrumed on the main frame and pivoted on the rack bar and on the carriage, means for shifting the carriage pivot towards and from the rack bar for varying the extent of the longitudinal movement of the carriage relative to said rack bar, and means for locking said carriage pivot in a shifted position. 5
27. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack bar during each space movement of the latter including a multiplying lever fulcrumed on the main frame and pivoted on the rack bar and on the carriage, means including a rack and pinion mounted on the carriage for shifting the carriage pivot towards and from the rack bar for varying the extent of the longitudinal movement of the carriage relative to said rack bar, and means for locking said carriage pivot in a shifted position. 10
28. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack bar during each space movement of the latter including a multiplying lever having pivotal connections with the rack bar and with the carriage, means for shifting said lever longitudinally to vary the distance between said pivots and thereby increase or decrease the longitudinal movement of the carriage relative to the rack bar, and means for locking said carriage pivot in a shifted position. 15
29. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a movement of the carriage relative to the rack bar during each space movement of the latter including a pivot plate movably mounted on the carriage, and a multiplying lever slidably fulcrumed on the main frame and having pivotal connections with the rack bar and with the plate, means for moving the plate and the lever to shift the carriage pivot relative to the rack bar pivot and thereby increase or decrease the longitudinal movement of the carriage relative to the rack bar, and means for locking said carriage pivot in a shifted position. 20
30. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack bar during each space movement of the latter including a multiplying lever fulcrumed on the main frame and pivoted on the rack bar and on the carriage, means for shifting the carriage pivot towards and from the rack bar for varying the extent of the longitudinal movement of the carriage relative to said rack bar, and means for locking said carriage pivot in a shifted position. 25
31. A carriage feeding mechanism for typewriting machines comprising the combination with a main frame, of a carriage mounted thereon for letter space movements, an escapement mechanism for the carriage including a rack bar mounted thereon for relative longitudinal movements, a bracket arm rigidly connected to the main frame and extending rearwardly from one end thereof, a bracket extending laterally from the adjacent end of the carriage, means for effecting a movement of the carriage relative to the rack bar during each space movement of the latter including a pivot plate slidably mounted on the carriage bracket for movements in a straight line extending diagonally to the longitudinal axis of the rack bar, a multiplying lever slidably fulcrumed on the main frame arm and having pivotal connections with the rack bar and with the plate, means mounted on the carriage bracket and having a rack and pinion connection with the plate for moving the plate and the lever to shift the carriage pivot relative to the rack bar pivot and thereby increase or decrease the longitudinal movement of the carriage relative to the rack bar, and means for locking said carriage pivot in a shifted position. 30
32. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, and control means for varying the ratio of said arms. 35
33. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, and means for varying the ratio of said arms including a rotary control element mounted on the carriage, said control element being provided with a circumferential series of spaced character space indicating numerals indicative of predetermined positions of adjustment of said lever connection. 40
34. A carriage feeding mechanism for typewriting machines comprising the combination with a main frame, of a carriage mounted thereon for letter space movements, an escapement mechanism for the carriage including a rack bar mounted thereon for relative longitudinal movements, 45

and a variable multiplying lever connection between the rack bar, the main frame, and the carriage, said lever having a lever arm between the rack bar and the carriage and a lever arm between the rack bar and the main frame, means for varying the ratio of said arms including a rotary control element mounted on the carriage, said control element being provided with a circumferential series of spaced character space indicating numerals indicative of predetermined positions of adjustment of said lever connection, and a stationary pointer mounted on the carriage for cooperation with said numerals.

35. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, and a variable multiplying lever connection between the rack bar, the main frame, and the carriage, said lever having a lever arm between the rack bar and the carriage and a lever arm between the rack bar and the main frame, control means for varying the ratio of said arms, and means for locking said control means in a predetermined position of adjustment.

36. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, means for varying the ratio of said arms including a rotary control element mounted on the carriage for adjusting said variable lever connection, said control element being provided with a circumferential series of spaced character space indicating numerals indicative of predetermined positions of adjustment of said lever connection, a stationary pointer mounted on the carriage for cooperation with said numerals, and cooperating means between the rotary control element and the pointer for locking said rotary control element in a predetermined position of adjustment.

37. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, means for varying the ratio of said arms including a rotary control element mounted on the carriage for adjusting said variable lever connection, said control element being provided with a circumferential series of spaced character space indicating numerals indicative of predetermined positions of adjustment of said lever connection, said rotary control element being also provided with a circumferential series of openings corresponding in number and in spacing to the indicating numerals, and means mounted on the carriage for cooperation with said openings to lock

the control element in any predetermined position of adjustment.

38. A carriage feeding mechanism for typewriting machines comprising the combination with a main frame, of a carriage mounted thereon for letter space movements, an escapement mechanism for the carriage including a rack bar mounted on the carriage for longitudinal movements relative to the carriage, means for effecting a movement of the carriage relative to the rack bar during each space movement of the latter including a multiplying lever fulcrumed on the main frame and pivoted on the rack bar and on the carriage, a carriage-mounted rack and pinion for shifting the carriage pivot towards and from the rack bar for varying the extent of the longitudinal movement of the carriage relative to said rack bar, and a rotary control element operatively connected to said pinion.

39. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, means for varying the ratio of said arms including a rotary control element mounted on the carriage, said element being provided with a plurality of circumferential series of spaced character space indicating numerals arranged in parallelism for different lengths of justified line copies, the numbers of said numerals differing in each series and being indicative of predetermined positions of adjustment of said lever connection.

40. A carriage feeding mechanism for typewriting machines comprising the combination with a main frame of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, means for varying the ratio of said arms including a rotary control element mounted on the carriage for adjusting said variable lever connection, said element being provided with a plurality of circumferential series of spaced character space indicating numerals arranged in parallelism for different lengths of justified line copies, the numbers of said numerals differing in each series and being indicative of predetermined positions of adjustment of said lever connection, and a pointer mounted on the carriage for movements from one series of numerals to another for cooperation with any numeral in a selected series.

41. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever

arm between the rack bar and the main frame, means for varying the ratio of said arms including a rotary control element mounted on the carriage for adjusting said variable lever connection, said element being provided with a plurality of circumferential series of spaced character space indicating numerals arranged in parallelism for different lengths of justified line copies, the numbers of said numerals differing in each series and being indicative of predetermined positions of adjustment of said lever connection, and means for locking said rotary control element in a predetermined position of adjustment defined by a selected numeral in any one of said series.

42. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar, the main frame, and the carriage, said lever having a lever arm between the rack bar and the carriage and a lever arm between the rack bar and the main frame, means for varying the ratio of said arms including a rotary control element mounted on the carriage for adjusting said variable lever connection, said element being provided with a plurality of circumferential series of spaced character space indicating numerals arranged in parallelism for different lengths of justified line copies, the numbers of said numerals differing in each series and being indicative of predetermined positions of adjustment of said lever connection, a pointer mounted on the carriage for movements from one series of numerals to another for cooperation with any numeral in a selected series, and cooperating means between the rotary control element and the pointer for locking the element in a predetermined position of adjustment defined by a selected numeral in any one of said series and for locking the pointer in its adjusted position.

43. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar and the carriage, a control element for adjusting said variable lever connection mounted on the carriage for rotation about a vertical axis, said element being provided with a plurality of circumferential series of spaced character space indicating numerals arranged in parallelism for different lengths of justified line copies, the numbers of said numerals differing in each series and being indicative of predetermined positions of adjustment of said lever connection, said rotary control element being also provided with a circumferential series of openings disposed above the space indicating numerals and corresponding in number and in spacing to the indicating numerals, an arm pivoted on the carriage to swing about a horizontal pivot, a pointer mounted on said arm to swing about a horizontal pivot for movements from one series of numerals to another for cooperation with any numeral in any series, and a pin fixed to said arm for cooperation with an opening corresponding to the selected numeral for locking the control element in its position of adjustment.

44. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar and the carriage, a control element for adjusting said variable lever connection mounted on the carriage for rotation about a vertical axis, said element being provided with a plurality of circumferential series of spaced character space indicating numerals arranged in parallelism for different lengths of justified line copies, the numbers of said numerals differing in each series and being indicative of predetermined positions of adjustment of said lever connection, said rotary control element being also provided with a circumferential series of openings disposed above the space indicating numerals and corresponding in number and in spacing to the indicating numerals, an arm pivoted on the carriage to swing about a horizontal pivot, a pointer mounted on said arm to swing about a horizontal pivot for movements from one series of numerals to another for cooperation with any numeral in any series, stop means mounted on the carriage for limiting the swinging movement of said arm, and a pin fixed to said arm for cooperation with an opening corresponding to the selected numeral for locking the control element in its position of adjustment.

45. A carriage feeding mechanism for typewriting machines comprising the combination with a main frame, of a carriage mounted thereon for letter space movements, an escapement mechanism for the carriage including a rack bar mounted thereon for relative longitudinal movements, and a variable multiplying lever connection between the rack bar and the carriage, a control element for adjusting said variable lever connection mounted on the carriage for rotation about a vertical axis, said element being provided with a plurality of circumferential series of spaced character space indicating numerals arranged in parallelism for different lengths of justified line copies, the numbers of said numerals differing in each series and being indicative of predetermined positions of adjustment of said lever connection, said rotary control element being also provided with a circumferential series of openings disposed above the space indicating numerals and corresponding in number and in spacing to the indicating numerals, an arm pivoted on the carriage to swing about a horizontal pivot, a pointer mounted on said arm to swing about a horizontal pivot for movements from one series of numerals to another for cooperation with any numeral in any series, an indicator plate mounted on the carriage in front of said series of openings and provided with a series of vertically spaced line length indicia, the spaces corresponding to the spaces between the series of space indicating numerals, a pointer fixed to said arm for cooperation with said indicia, and a pin fixed to said arm for cooperation with an opening corresponding to the selected numeral for locking the control element in its position of adjustment.

46. A carriage feeding mechanism for typewriting machines comprising the combination with a main frame, of a carriage mounted thereon for letter space movements, an escapement mechanism for the carriage including a rack bar mounted thereon for relative longitudinal movements, means for effecting a movement of the

carriage relative to the rack bar during each space movement of the latter including a multiplying lever having pivotal connections with the rack bar and with the carriage, means for shifting said lever longitudinally to vary the distance between said pivots and thereby increase or decrease the longitudinal movement of the carriage

relative to the rack bar, and means for indicating the setting of the lever-shifting means required for effecting a desired space justification in a line of any one of a plurality of different line lengths.

GEORGE F. HANDLEY.
